GAME DIE

William D. Hulser, 809 N. Spaulding,
Los Angeles, Calif. 90046

Filed Nov. 15, 1966, Ser. No. 4,669

Term of patent 3½ years

(Cl. D34—5)

FIG. 1.

FIG. 2.

FIG. 1 is an elevational view, taken from one side of the game die and illustrating half of the faces thereof; and

FIG. 2 is an elevational view taken from the rear of FIG. 1 and illustrating the other faces of the design.

I claim:

The ornamental design for a game die, substantially as shown.
